(57) **CLAIM**

The ornamental design for a brush with angled wave-shaped bristles, as shown and described.

DESCRIPTION

FIG. 1 is a front elevational view of a brush with angled wave-shaped bristles showing my new design, the broken lines showing a ferrule and a handle being for illustrative purposes only and forming no part of the claimed design; FIG. 2 is a top plan view thereof; and,

FIG. 3 is a right side view of FIG. 1, of which the left side, with the exception of the lengths of the vertical extention and the angled top of the bristles, is a mirror image.
